CLAIM

The ornamental design for an ultra-sonic welding horn,
as shown.

DESCRIPTION

FIG. 1 is a perspective view of ultra-sonic welding horn
embodiment my new design;

FIG. 2 is an end view; and,

FIG. 3 is a fragmentary sectional view greatly enlarged
taken along lines 3—3 of FIG. 2.

The broken line showing of the welding horn upper
body is for illustrative purposes only and forms no part
of the claimed design.
